UNITED STATES PATENT OFFICE.

JOHN HELMING, OF CINCINNATI, OHIO.

MOLDED SHOE-COUNTER.

1,197,624.

Specification of Letters Patent. Patented Sept. 12, 1916.

Application filed January 5, 1916. Serial No. 70,522.

To all whom it may concern:

Be it known that I, JOHN HELMING, a citizen of the United States, and residing at Cincinnati, in the county of Hamilton and State of Ohio, have invented a new and useful Improvement in Molded Shoe-Counters, of which the following specification is a full disclosure.

This invention relates to molded counters for shoes.

An object of the invention is in adapting a molded counter for use in turned shoes, capable of being applied in position during the process of shoe manufacture, primarily after the upper and sole have been stitched together and turned for second lasting.

Another object of the invention contemplates connecting or joining the wing ends of the counter, at its seat margins, preferably providing a strap or tie member secured to the opposing wing ends, qualifying as a means for anchoring the counter properly in its position within the shoe, preventing a shifting or creeping action and equalizing the counter strains upon opposite sides of the foot of the wearer, resulting in more permanently maintaining the shape of the shoe after it is worn.

Various other features of the invention will be more fully revealed from the description of the accompanying drawings, forming a part hereof, disclosing a preferred embodiment of the invention, and in such drawings like characters of reference denote corresponding parts throughout the several views, of which:

Figure 1 is a view of a molded counter containing my improvement. Fig. 2 is a section on line 2, 2, Fig. 1.

This invention, from a generic aspect as an article of manufacture, may be of general utility in all the different types of shoe manufacture as welt, McKay, etc., although it finds especial favor in the manufacture of turned shoes. In such latter use, it is disclosed and described as a feature to the invention described and claimed in a prior application, filed by me on October 15, 1915, Serial No. 55,926, treating with

a process of manufacturing turned shoes, and in the application of a molded counter in turned shoes. In such connection, the invention herein is disclosed and referred to, although represented in a modified form 55 as to the details of construction from that herein.

As certain features of the counter may be more readily apparent in its use in the manufacture of turned shoes, the description will be confined to such use.

Referring to Fig. 1 of the drawings, the counter comprises a curved body portion 1 developing into relatively opposite wings 2, 3, and provided with the marginal inwardly turned base or seat flange 4, made from any suitable material, treated, cut to pattern and pressed into shape by any process or in any manner known in the art. The counter, as thus far described, represents a finished commercial product now largely used in the manufacture of welt shoes, possessing many advantages well known to and recognized by the trade, without requiring further comment. 75

The ends of the wings 2, 3, are joined or united by a strap or connector secured to the seat flange, and, as illustrated, comprises a folded tape 5 lapping over the end of the flange of each wing and secured thereto by 80 a staple 6. This presents the folded edge forwardly or outwardly and assists in guiding the counter as it is being inserted in the manufacture of a turned shoe, under the process as described in the aforesaid application. The counter, in such process, is inserted between the layers forming the upper, as the outer and lining layers, after the upper has been stitched to the outer soles and in a condition for a second lasting. 90 The strap 5 extends transversely between the shank piece and the shank portion of the sole and thus anchors the ends of the counter wings against any separating or upward motion in the shoe or creaking action between the upper layers. The counter at such end, therefore, completely embraces the foot at the shank portion of the shoe, assists in sustaining the foot arch, maintains 95 the original shape of the counter, all of 100

which add to the comfort of the wearer. It is also advantageous in maintaining the shape of the counter when nested together for packing and shipping purposes as an 5 article of manufacture.

Having described my invention, I claim:—

A molded counter as an article of manufacture, having a marginal seat flange, and a tape folded longitudinally with the fold

portions embracing opposite end portions of 10 the flange and secured thereto.

In witness whereof, I hereunto subscribe my name, as attested by the two subscribing witnesses.

JOHN HELMING.
